(57) **CLAIM**

The ornamental design for a window shutter, as shown and described.

DESCRIPTION

FIG. 1 is a front perspective view of a window shutter showing my new design;

FIG. 2 is a front view, the back being plain and unadorned; FIG. 3 is a side view, the opposite side being a mirror image thereof; and,

FIG. 4 is a top view, the bottom being a mirror image thereof.

The broken lines in the drawing depict environment only and forms no part of the claimed design.
